UNITED STATES PATENT OFFICE.

FREDERICK W. COX, OF WILKINSBURG, PENNSYLVANIA, ASSIGNOR TO WESTINGHOUSE ELECTRIC & MANUFACTURING COMPANY, A CORPORATION OF PENNSYLVANIA.

COMMUTATOR FOR DYNAMO-ELECTRIC MACHINES.

No. 920,920.

Specification of Letters Patent.

Patented May 11, 1909.

Application filed April 4, 1908. Serial No. 309,901.

To all whom it may concern:

Be it known that I, FREDERICK W. Cox, a citizen of the United States, and a resident of Wilkinsburg, in the county of Allegheny and 5 State of Pennsylvania, have invented a new and useful Improvement in Commutators for Dynamo-Electric Machines, of which the following is a specification.

My invention relates to commutators for 10 dynamo-electric machines and it has for its object to provide improved means for securing and supporting the segments of relatively long commutators such as are subjected to high speeds in operation.

15 Commutators for dynamo-electric machines, as heretofore constructed, have usually comprised a plurality of bars or segments and a supporting bushing having an annular V-shaped projection at one end, or a clamping 20 ring which was stationary relative thereto, and an adjustable clamping ring near its other extremity. The clamping rings which were forced together by any convenient means, such as a nut, screw-threaded onto 25 the outer extremity of the bushing, or clamping bolts which passed through holes in the rings, were adapted to engage complementary notches in the commutator segments.

If this construction is used for very long 30 commutators, such as are required for machines which are adapted to receive or to deliver relatively large values of electric current, the commutator segments show a tendency to bulge outwardly in the middle by 35 reason of the centrifugal forces to which they are subjected, particularly in high speed operation. This difficulty has been avoided in some instances by fastening a ring around the middle of the outer surface of the commutator but such a ring diminishes the surface of the commutator which is available 40 for engagement with brushes or current collectors and must be insulated from the commutator segments.

45 According to my present invention I fasten the commutator segments securely in position without the use of an external ring and employ a supporting bushing which is similar to those employed in the prior art.

50 Figure 1 of the accompanying drawings is a sectional view, in a longitudinal plane, of one-half of a commutator constructed in accordance with my invention and Fig. 2 is a similar view which discloses additional means 55 for securely clamping in position commutator

segments of extreme length. Fig. 3 is a plan view of the commutator bar clamping means shown in Fig. 2, the commutator bars being omitted and portions of some of the bolts being broken away.

60 Referring to Fig. 1, a bushing 1, which may be rigidly attached to the shaft of a dynamo-electric machine, is provided at one end with an annular V-shaped projection 2. An adjustable V-shaped ring 3 is mounted on 65 the bushing 1 near its opposite end and, together with the V-shaped projection 2, serves to firmly support the ends of a plurality of commutator segments 4. The segments 4 are assembled in the form of a cylinder and 70 are provided with V-shaped notches 5 and 6 which are, respectively, engaged by a V-shaped ring 3 and the V-shaped projection 2.

75 In order to hold the middle of the commutator segments in position, two similar, intermediate adjustable V-shaped rings 7 and 8 are mounted upon the bushing 1 and respectively engage notches 9 and 10 which are formed in the commutator segments. Holes 11 and 12 are provided in the intermediate 80 rings 7 and 8 through which clamping bolts 13 and 14 may pass and the V-shaped ring 3 and the projection 2 are also provided with similar openings 15 and 16 in alignment with the holes in the intermediate rings. The 85 bolts 14 are adapted to draw the intermediate ring 7 toward the stationary projection 2 on the bushing and the bolts 13 are adapted to draw the intermediate ring 8 and the end ring 3 together. In this way, all the supporting 90 V-shaped rings are drawn into the notches in the commutator segments with which they are adapted to engage. The 95 holes in the rings 7 and 8 are in alignment with each other and are disposed at substantially equal intervals about the rings. The bolts 13 and 14 are inserted in alternate holes in order to avoid interference and to distribute the forces exerted upon the rings.

100 Referring to Fig. 2 the commutator illustrated, is similar to that of Fig. 1 except that the ends of the commutator segments are beveled and supporting rings 17 and 18 are bolted, respectively, to the V-shaped ring 3 and the projection 2 of the bushing, these 105 rings being provided with annular projections 19 which are adapted to engage the beveled ends of the commutator segments. The rings 17 and 18 serve, principally, to hold the ends of the commutator segments 110

in position and will probably be utilized only with commutators of extreme length.

Although I have shown and described a specific arrangement I desire that only such limitations be imposed as are indicated in the appended claims.

I claim as my invention:

1. In a commutator, the combination with segments, and a support therefor having a non-adjustable clamping ring, and a complementary adjustable clamping ring for said segments, of auxiliary clamping rings which engage intermediate portions of the segments.
- 15 2. In a commutator, the combination with segments, and a support therefor having an integral clamping ring at or near one end, and a complementary adjustable clamping ring at or near the other end, of auxiliary adjustable clamping rings which engage intermediate projections on the segments.
- 20 3. In a commutator, the combination with segments, and a support therefor having a non-adjustable clamping ring at or near one end, and a complementary adjustable clamping ring at or near the other end, of a pair of auxiliary adjustable and opposing clamping rings which engage intermediate projections on the segments and means for exerting opposing pressures against said auxiliary rings.
- 25 4. In a commutator, the combination with segments, a support, a clamping ring that is stationary relative to said support and a complementary, adjustable clamping ring for said segments, of intermediate clamping rings therefor and means for exerting pressure upon alternate rings toward each other.
- 30 5. In a commutator, the combination with segments, a support, a clamping ring that is stationary relative to said support and a complementary, adjustable clamping ring for said segments, of a pair of intermediate adjustable and opposing clamping rings therefor and means tending to move alternate rings toward each other.
- 35 6. In a commutator, the combination with

segments, a support and four longitudinally spaced clamping rings for said segments, of means tending to move alternate rings toward each other.

7. In a commutator, the combination with segments, a support, and four clamping rings for said segments, of bolts tending to move alternate rings toward each other and projecting loosely through holes in the intermediate rings.

8. In a commutator, the combination with segments, a supporting and clamping ring that is stationary relative thereto, a complementary adjustable clamping ring near the opposite end of the support, of a pair of complementary intermediate clamping rings having corresponding holes disposed at intervals around the several rings and in alinement with each other, and bolts which tend to move alternate rings toward each other and which pass loosely through the holes in the intermediate rings.

9. The combination with a commutator bushing having an annular V-shaped projection near its inner extremity, of a plurality of adjustable V-shaped rings one of which is adapted to be adjusted away from the V-shaped projection and the others of which are adapted to be adjusted toward the V-shaped projection.

10. The combination with a commutator bushing having a V-shaped ring near its inner end, of a V-shaped ring adjustably mounted upon the opposite end of the bushing, two oppositely disposed V-shaped rings adjustably mounted upon the bushing intermediate its ends, and clamping bolts between each end ring and the opposing intermediate ring.

In testimony whereof, I have hereunto subscribed my name this 28th day of March, 1906.

FREDERICK W. COX.
